FIG. 3

FIG. 1 is a fragmentary perspective of an exterior lamp showing my new design, the post being broken away to indicate indeterminate length;

FIG. 2 is an enlarged fragmentary top plan view thereof; and

FIG. 3 is an enlarged fragmentary side elevational view thereof, the top being lifted for purposes of disclosure.

The lamp is fragmentarily shown in FIGS. 2 and 3 for purposes of disclosure. The post is fragmentarily shown in FIG. 3 for convenience of illustration.

I claim:

The ornamental design of an exterior lamp, as shown and described.
